UNITED STATES PATENT OFFICE.

GUSTAVE E. VILLARET, OF LEONIA, NEW JERSEY, ASSIGNOR TO HALCOLITE COMPANY, INC., A CORPORATION OF NEW YORK.

DESIGN FOR A LIGHTING-FIXTURE PLATE OR ARTICLE OF ANALOGOUS NATURE.

Application filed December 12, 1928. Serial No. 29,227. Term of patent 7 years.

To all whom it may concern:

Be it known that I, GUSTAVE E. VILLARET, a citizen of the United States, and a resident of Leonia, county of Bergen, and State of New Jersey, have invented a new, original, and ornamental Design for a Lighting-Fixture Plate or Article of Analogous Nature, of which the following is a specification, reference being had to the accompanying drawing, forming a part thereof.

In the drawing:

Figure 1 is an inverted plan view of the lighting fixture plate or article of analogous nature, the parts shown in full line outline being ornamented in the same manner as the parts more fully illustrated;

Figure 2 is a diagrammatic edge view.

I claim:

The ornamental design for a lighting fixture plate or article of analogous nature substantially as shown and described.

GUSTAVE E. VILLARET.
